WINDOW LATCH

Filed June 23, 1928

Fig. 1.

Fig. 2.

UNITED STATES PATENT OFFICE

HENRY LORENZEN, OF CRETE, ILLINOIS

WINDOW LATCH

Application filed June 23, 1928. Serial No. 287,707.

This invention relates to certain novel improvements in window latches, and has for its principal object the provision of an improved construction of this character which will be highly efficient in use and economical in manufacture.

Among the several objects of this invention is to provide a window latch which when once disposed in latched position will be wedged against one of the sash rails of a window construction when either of the sashes of the window construction is moved to opened position thereby preventing unauthorized movement of either of the window sashes.

Other objects will appear hereinafter.

The invention consists in the novel combination and arrangement of parts to be hereinafter described and claimed.

The invention will be best understood by reference to the accompanying drawings, wherein a preferred form of construction is shown and in which:

Fig. 1 is a fragmentary elevational view of a window construction showing my improved window latch associated therewith;

Fig. 2 is a fragmentary sectional detail view of the same taken substantially on line 2-2 of Figure 1;

Fig. 3 is a fragmentary sectional detail view taken substantially on the line 3-3 of Figure 2; and

Fig. 4 is a sectional view taken approximately on line 4-4, Fig. 2, looking in the direction of the arrows.

In the drawings I have shown a fragmentary elevational view of a window construction, which window construction includes a jamb 10, an upper sash, 11, and a lower sash 12, having associated therewith the usual sash cords 13. With this window construction I associate my improved window latch which includes a bracket 14 provided with a bottom flange 15 secured to the top rail 16 of the sash 12 by means of screw elements 17. This bracket further includes a flange 18 which is disposed in parallel relation with the jamb 10 and which has its upper end portion 19 angled and bifurcated as at 20, to

provide a recess for the reception of the window cord 13.

Supported by this flange 18 is a pin 21 having wound thereabout a spring 22. One end of the spring 22 is fixed to the flange 18 as at 23 and the other end 24 of the spring is fixed to a cam 25 as at 26. This cam 25 is mounted for floating movement on the pin 21, as shown in Fig. 3, and has its cam edge 26 covered with a rubber or other resilient ring 27 for reasons hereinafter more fully set forth. The pin carries as at 28 operating handle 29 which works in a recess 27 formed in the cam edge which provides a shoulder 31 against which the handle 29 is adapted to abut.

The bracket 14 is mounted upon the lower window sash 12 as best shown in Fig. 1, and to dispose the cam edge of the cam 25 into position to engage the rail 30 of the upper sash, the handle 29 is moved in a direction to rotate the pin 21. The handle 29 thus engages the shoulder 31 and thereby rotates the cam against the action of the spring. In this manner the cam is rotated about the pin 21 to dispose its cam edge against the rail 30. Upon movement of either of the upper or lower sashes of the window construction, the cam being in engagement with the rail 30 will be caused to further rotate so as to wedge itself into a firmer position against the rail thus preventing the movement of either of the window sashes. To move the cam edge from engagement with the rail, there is provided on the cam a lip 31 which may be engaged by the finger of the hand so that the cam may be rotated in an opposite direction to dispose its cam edge from wedged position with respect to the rail.

From the foregoing description taken in connection with the accompanying drawings, it will be manifest that I have provided a window lock which may be efficient in operation and economical in manufacture.

While I have illustrated and described the preferred form of carrying my invention into effect, this is capable of variations and modifications without departing from the spirit of the invention. I, therefore, do not wish to be limited to the precise details of construction set forth herein, but desire to

avail myself of such variations and modifications as come within the scope of the appended claims.

Having thus described my invention, what I claim as new and desire to protect by Letters Patent, is:

1. In a device of the character stated, a plate including an upwardly extending portion, a pin mounted in said upwardly extending portion, a cam eccentrically mounted for floating movement on said pin, a spring disposed around said pin, said spring having one end thereof connected to said upwardly extending portion and the opposite end thereof connected to said cam, said cam having a slot formed in one face thereof providing a shoulder, and a handle carried by said pin including a portion adapted to travel in said slot whereby said handle may be moved to engage said shoulder to rotate said cam against the action of said spring.

2. In a device of the character stated, a plate including an upwardly extending portion, a pin mounted in said upwardly extending portion, a cam eccentrically mounted for floating movement on said pin, a spring disposed around said pin, said spring having one end thereof connected to said upwardly extending portion and the opposite end thereof connected to said cam, said cam having a slot formed in one face thereof providing a shoulder, and a handle carried by said pin including a portion adapted to travel in said slot whereby said handle may be moved to engage said shoulder to rotate said cam against the action of said spring, said cam having a covering of resilient material on the periphery thereof.

In testimony whereof I affix my signature.

40 HENRY LORENZEN.
